ADJUSTABLE DIFFERENTIAL SWITCH ACTUATOR

William J. Williams, Wilmette, Ill.

Application February 1, 1956, Serial No. 562,849

7 Claims. (Cl. 200—166)

This invention relates to an adjustable mechanism for operating switches or switching mechanism with precision accuracy for making and breaking or controlling switch operations at different speeds or under different conditions, controlling such operations together with differentials between the making and breaking, or changing of electrical circuits by such switch or switching mechanism.

More specifically, I provide by this invention adjustable switch operating mechanisms comprising a compound lever linkage and special operating arrangement adjustable to precision accuracy for making and breaking or controlling the switch operations for different conditions under control of suitable mechanisms responsive to such conditions or changes thereof. By my invention I can accurately determine the differentials between the making and breaking, or changing of electrical circuits effected by such switches or switching mechanisms.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawings of a form of the invention, which may be preferred, in which:

Figure I is an elevation partly in section showing a pressure operated device in operative relation with a switch using my means of actuating the adjustable differential switch operating mechanism.

Figure II is a partial elevation of a temperature responsive means for my switch operating mechanism.

Figure III is a sectional elevation of a modification of my invention using a speed responsive controlling device.

Figure IV is an end elevation of the form of my invention shown in Figure I.

Figure V is a section taken substantially on the lines V—V of Figures I and III.

Figure VI is a section taken substantially on the line VI—VI of Figure I.

Figure VII is an enlarged perspective view of one of the levers of my invention.

Figure VIII is a section taken substantially on the lines VIII—VIII of Figure I.

Figure IX is a section taken substantially on the lines IX—IX of Figure III.

Figure X is a section taken substantially on the lines X—X of Figure III.

Figure XI is a diagrammatic showing of the action of the form of my invention shown in Figure III, under various operating conditions.

Referring to the drawings, in Figure I, I show an assembly of my invention using a self returning or snap switch unit indicated at 10 having a depending operating pin 11, and a double lever adjusting and operating mechanism 12 (see Fig. 1) having an actuating pin 14 adapted to be moved by a plunger 15 which moves upwardly and

2

downwardly according, in this particular instance, to a pressure responsive device 16. In the embodiment illustrated of my precision and accurately adjustable mechanism 12 for controlling the action of switch pin 11 from

5 the plunger 15, I provide an L-shaped support 20 to the upper part 21 of which the switch unit 10 may be secured as by the screws 22 (see Figure IV), the lower part 23 of the L-shaped support is secured to the top of the condition responsive device as shown.

10 The upper L portion 21 of the support carries at opposite sides bearings, the one 24 at the righthand and the other, 25 at the left side for carrying the transverse screw threaded lever supporting shaft 27, said shaft being free to rotate in said bearings and having the head 28 for adjustment purposes, the other end being provided with a pair of locking nuts 29.

15 My operating and adjustable mechanism includes two cooperating levers, one of said levers 30 pivoted at the left side in Figure I to a pivotal stud 31 (see Figure 20 VIII) carried by the bearing 25 as shown, said pin and bearing 25 being fixed as shown at 32 to part 21 on support 20. This lever 30 carries a slider element 34 having a contacting button 34' for actuating the switch pin 11. For different installations I change the position of the 25 slider 34 as may be required or desirable—friction retaining the slider in fixed position.

20 The other end of shaft 27 carries the other lever 37 pivoted at one end to an adjustable pivot 38 which as shown in Figure VI may be formed of a stud 39 extending forwardly of a block 40 screw threaded on shaft 27. The underside of lever 37 contacts the pressure operated pin 14 to be actuated therefrom (see Figure I).

25 To operate the first lever 30 from the second adjustable lever 37, I provide on said lever 37 a sliding contact button 42 adapted to be frictionally held in place on said lever, the details of this mounting being a sliding clamp 43 which may be moved to various positions on lever 37—see Figure VII.

30 Thus it will be seen that I can adjust the button 42 on 40 the adjustable or second lever 37 to approximately a desired position and then by turning screw shaft 27 by its slotted head 28, the pivotal bearing 38 for the second lever 37 may be accurately adjusted to vary the effective length thereof. This simultaneously adjusts the effective 45 length of the first lever 30 since it varies the position at which the button 42 of lever 37 contacts the first lever 30.

35 In operation the variable pressure responsive plunger 15 actuates pin 14, swinging lever 37 about its pivot 38 whereupon the button 42 also swings the first lever 30 about its pivot 31. Thereupon button 34' contacts switch pin 11 and actuates the same. Since the break away inertia of the snap switch 10 is greater than that required to hold the switch in its changed position, upon reversal of plunger 15 (due to a drop in pressure) the switch pin 11 will not be lowered until the pressure on plunger drops somewhat below that required to move the pin upwardly. This gives a differential between the first operation of switch 10 and its reversal.

40 In Figure II, I show a similar arrangement to Figure I except that in Figure II the plunger 15 is operated by a temperature responsive device indicated at 18.

45 In the embodiment of Figure III, I show a governor for operating the plunger 15 and also employ the two cooperating levers, one of said levers 30 pivoted at the left side as in Figure I to a pivotal stud 31 carried by the bearing 25 as shown, said pin and bearing 25 being fixed as shown at 32 to part 21 of support 20. This lever 30 carries a flat leaf spring 36 fixed thereto at its pivotal end as shown at 35, said spring 36 contacting the switch pin 11 and having a curled free end resting on lever 30 and slideable thereon. For different installations

to obtain different make and break speeds for the switch operation I change the size, thickness and flexibility of the spring 36 as may be required or desirable. The other parts of my two lever switch actuating mechanism are the same as in Figure I. In Figure III the plunger 15 is operated by a speed responsive device or governor 17.

In this form of my invention the plunger 15 upon increasing speeds, actuates pin 14, swinging lever 37 about its pivot 38, whereupon the button 42 also swings the first lever 30 about its pivot 31.

In Figure XI, the operation of the embodiment of Figure III is diagrammatically illustrated showing that as the lever 30 carrying spring 36 moves upward it compresses or flattens said spring 36 until the potential energy stored in spring 36 is sufficient to overcome the resistance of the switch unit 10 and the spring contacting the switch pin 11 thereupon moves the snap switch 10 to close its contacts. This action is predetermined by the speed of the governor 17 according to the setting of the adjustable lever mechanism and the resiliency of the particular spring 36 used. At this point the pressure required to hold the switch in contact (see second diagram from left Figure XI) is very small compared to the operating pressure just described, consequently, the stored energy or build-up of spring 36 readily holds the switch in contact or closed position. Moreover, the mechanism will not only hold the switch closed at said predetermined speeds or greater, but also over a large range of reduced speeds therefrom as shown in the diagram the third from the left in Figure XI. Then when the speed of the governor is thereafter reduced to a predetermined lower point, the switch pin 11 recedes to a point where the inherent action of the snap switch 10 overcomes the greatly reduced holding power value of spring 36 at which time the switch 10 will reset with a snap action due to the inherent construction of the switch itself. This action is illustrated in the extreme right-hand diagram of Figure XI.

For various installations, as desired, different springs 36 may be used so that with springs with different resiliency will effect in conjunction with the lever and governor mechanism disclosed a wide range of switch operation (closing and opening) at various differential speeds.

It is apparent that, within the scope of the invention, modifications and different arrangements may be made other than is herein disclosed, and the present disclosure is illustrative merely, the invention comprehending all variations thereof.

What I claim is:

1. In an adjustable switch operating mechanism, adapted to be operated by a condition responsive device to operate the closing of the contacts of a switch dependent on a predetermined condition and the opening of said switch dependent upon different conditions, the combination of a pair of cooperating movable levers; means to pivotally support in fixed position of adjustment both said levers, one of said levers adapted to operate the switch, the other lever arranged for operating said first mentioned lever, the effective operative relation of the fulcrums of said levers being adjustable; and means controlled by said responsive device to actuate said second lever.

2. In an adjustable switch operating mechanism, adapted to be operated by a device responsive to varying conditions to make and break a switch upon occurrence of different conditions, the combination of a pair of movable levers; means to pivotally support in fixed position of adjustment said levers, said means including a longitudinal screw threaded shaft, one of said levers arranged to operate the switch; adjustable means carried by the other lever for actuating said first lever, said last mentioned lever having a screw threaded pivotal bearing mounted on said screw threaded shaft for adjustably supporting the pivotal end of said second lever, means controlled by the condition responsive device to operate said

second lever to cause said first lever to operate said switch and means to lock said threaded shaft in various positions of adjustment.

3. In a compound adjustable lever mechanism for operating a snap switch from a variable condition responsive device, said mechanism including a transverse screw threaded shaft, a combined support and pivot for a first lever at one end of said shaft, said support adapted to be fixed to the frame of said mechanism; a first lever mounted on said pivot and adapted for contacting the actuating pin of the switch; a support for the other end of said shaft; means to rotate said second lever around said pivot, actuated from said condition responsive device; a second lever having a screw threaded pivot carried by said shaft; means to prevent said pivot from turning; a slider carried by said second lever; means on said slider for operating said first lever; and means to rotate said screw threaded shaft to adjust said pivot and simultaneously change the effective fulcrum lengths of both said levers.

4. In a compound adjustable lever mechanism for operating a snap switch from a variable condition responsive device, said mechanism including a transverse shaft provided with screw threads, a combined support and pivot for a first lever at one end of said shaft, said support adapted to be fixed to the frame of said mechanism; a first lever on said pivot for contacting the actuating pin of the switch; a bearing support for the other end of said shaft permitting free rotation of said shaft therein; a second lever having a screw threaded pivot carried by said shaft at the screw threads thereof; means to rotate said second lever around said pivot, actuated from said condition responsive device; means to prevent said pivot from turning; a slider carried by said second lever; means on said slider for operating said first lever; means to rotate said shaft to adjust said pivot and change the effective fulcrum lengths of said levers; and means to lock said shaft in fixed position of adjustment.

5. In a compound adjustable lever mechanism for operating a snap switch from a variable condition responsive device, said mechanism including a transverse shaft provided with two screw threaded portions, a combined support and pivot for a first lever at one end of said shaft, said support adapted to be fixed to the frame of said mechanism; a first lever on said pivot for contacting the actuating pin of the switch; a bearing support for the other end of said shaft permitting free rotation of said shaft therein; a second lever having a screw threaded pivot carried by said shaft at one set of two screw threaded portions; means to rotate said second lever around said pivot, actuated from said condition responsive device; means to prevent said pivot from turning; a slider carried by said second lever; means on said slider for operating said first lever; means to rotate said shaft to adjust said pivot and change the effective fulcrum lengths of said levers; and a pair of locking nuts positioned at the other of said two sections of screw threads to lock said shaft in fixed position of adjustment.

6. In a compound adjustable lever mechanism for operating a snap switch for a variable condition responsive device, said mechanism including a transverse shaft provided with two screw threaded portions, a combined support and pivot for a first lever at one end of said shaft, said support adapted to be fixed to the frame of said mechanism; a first lever on said pivot for contacting the actuating pin of the switch; a bearing support for the other end of said shaft permitting free rotation of said shaft therein; a second lever having a screw threaded pivot carried by said shaft at one set of said two sets of screw threaded portions; means to prevent said pivot from turning; an approximately settable slider carried by said second lever; a substantially hemispherical button carried by said slider, said button adapted to contact said first lever to operate the same; and means to rotate said shaft to very accurately position said pivot and change

the effective fulcrum lengths of said levers after said slider has been approximately positioned.

7. In a compound adjustable lever mechanism for operating a snap switch from a variable condition responsive device, said mechanism including a transverse shaft provided with two screw threaded portions, a combined support and pivot for a first lever at one end of said shaft, said support adapted to be fixed to the frame of said mechanism; a first lever on said pivot for contacting the actuating pin of the switch; a bearing support for the other end of said shaft permitting free rotation of said shaft therein by providing relatively smooth cylindrical portions between said shaft and the opening in said support for carrying said shaft; a second lever having a screw threaded pivot carried by said shaft at one of said two sets of screw threaded portions; means to prevent said pivot from turning; an approximately settable slider carried by said second lever; an operating button adapted

10

15

to contact said first lever to operate the same; means to rotate said shaft to very accurately position said pivot and change the effective fulcrum lengths of said levers after said slider has been approximately positioned; and screw threaded locking means on the first mentioned screw threaded portion of said shaft adapted to lock said shaft in adjusted position by contact thereof with said first mentioned combined support and pivot.
